PARTITION COLLAPSER

Albert F. Shields, Forest Hills, N. Y., assignor to S & S Corrugated Paper Machinery Co., Inc., Brooklyn, N. Y., a corporation of New York

Application April 23, 1952, Serial No. 283,812

5 Claims. (Cl. 93—37)

This invention relates to a machine for collapsing and grouping partitions as they come from the partition assembling machine (more particularly an assembling machine of the type shown in my prior Patent No. 2,392,005).

In the packaging of articles of various types, it is sometimes necessary to provide individual compartments in the packaging container for individual articles as for example in the case of eggs, cartridges, bottles or other fragile or fragile articles.

To provide this compartmentalization, partitions are formed from a series of interlocking notched blanks which are inserted into the container.

Machines have been developed for assembling these partitions as shown, for example, by Patents Nos. 2,392,005 or 2,414,336. These machines produce assembled partitions at a rate so fast as to create handling difficulties at the take-off end of the machine in that a light bulky partition must be removed by hand, collapsed, and grouped with other partitions for shipment to the package user.

When this is done by hand so many operators are required to handle the output of a single machine as to require a large amount of floor space and even then to result in awkward working conditions.

It is a primary object of this invention to provide a machine for collapsing the assembled partitions as they come from the assembling machine.

An equally important object is to provide means for arranging the collapsed partitions to facilitate ready bundling for shipment.

A further object of this invention is to provide a machine which may readily handle partitions of different sizes.

These and other objects of the invention as will appear hereinafter are achieved by means of the mechanism disclosed in the following specification taken in connection with the drawings in which:

Figure 1 is a side elevation of the apparatus.

Figure 2 is a top plan view of the apparatus.

Figure 3 is a fragmentary side view similar to Figure 1 showing some of the collapsed partitions in edge piled relationship.

Figure 4 is a detail view of the partition orienter as seen in Figures 1 and 2.

Figure 5 shows a top plan view of the partition in its position prior to being collapsed.

Figure 6 shows a top plan view of the partition as it is being collapsed.

Referring now to the drawings, it is seen that a supporting framework 1 comprising uprights 2 and 3 and suitable horizontal bracing is provided to support a driven endless belt feeder conveyor 4.

To the right of said conveyor as seen in Figures 1 to 3 is seen a carriage 5 having rollers 6 and 7 riding on inclined tracks 8 and formed on the supporting framework. By means of weight 9 the carriage is biased toward the left as seen in Figures 1-3 due to the inclination of the

tracks. Collapsible abutment 10 serves to prevent movement of the carriage past a given limiting position. On the left-hand edge of the carriage as seen in Figures 1-3 is mounted vertical pressure plate 11 having extensions 33 for contacting the partitions.

Frame 12 supported on the framework has pivoted thereto through pivot 23 arm 13 carrying bearings 14 for roller 15. Deflector 16 is mounted by screws, rivets, or other suitable fastening means 34 adjacent to roller 15 and has extensions going into grooves 24 in roller 15 to prevent articles from being carried upwardly by the roller. Roller 15 may as shown comprise a plurality of sections 15a spring biased toward each other to permit the roller 15 to yield as the partition ends are driven out.

15 In this case stripper fingers 16 are not used.

Arm 13 is adjustably mounted on frame 12 to provide a means for adjusting the height of roller 15 with respect to conveyor 4 so as to permit the handling of various sized partitions. Adjustment is achieved by means of shaft 17 having its lower end threaded into tapped sleeve 18 pivotally fastened to arm 13 and journaled in bearing 19 pivotally mounted on frame 12. Shaft 17 may be turned to advance or retract the sleeve, thus raising or lowering the arm by means of adjusting wheel 20.

20 An orienter 21 having an adjustable finger 22 is supported on upright 3 whose operation will subsequently be discussed.

Conveyor 4 and roller 15 are power driven from a common source shown here by means of sprocket wheels 25, 30 26, 27, 28 and 29 and chains 30, 31 and 32 which may obviously be replaced by a myriad variety of gearing.

In employing the foregoing structure, partitions from the assembling machine are fed into conveyor feeder 4 which carries them in the direction of the arrows past

35 orienter 21 which engages the corner of the leading edge of the partition in the manner shown in Fig. 4. Since the conveyor continues to feed, in the direction shown by the arrows (see Figures 5 and 6) the partition 40 pivots about finger 22 thereby causing it to partially collapse 40 and to travel as shown in Figure 6.

On being fed further, the top surface of the partition is engaged by roller 15 which cooperates as an auxiliary feeder to the conveyor feeder and pushes the partition up against pressure plate 11. Since the plate 11 is forced in a direction opposite to the direction of feeding by weight 9, the partition on abutting against the plate is collapsed, being structurally weaker than any of the members exerting a force on it.

45 The collapsed partition backed up by the pressure plate 50 exerts a sufficient retarding force to collapse subsequently fed partitions. An edge pile is thus formed as seen in Figure 3. As the pile is built up, plate 11 mounted on carriage 5 is forced along track 8 providing room for additional collapsed partitions.

55 The plate 11 may, if desired, be made in sections so that its height may be varied to allow the partitions to extend above it. This allows the operator to place a cord around the partitions and form a bundle.

A structure is thus provided where a single operator 60 may readily handle the output of a partition assembling machine, removing bunches of collapsed partitions as required for packing and shipping.

In the foregoing I have described my invention solely in connection with a specific preferred embodiment thereof. Since many variations and modifications of my invention will now be apparent to those skilled in the art, I prefer to be bound not by the specific disclosure herein contained but only by the appended claims.

I claim:

1. Apparatus for collapsing partitions comprising an endless belt conveyor for feeding said partitions, a stop at the end of said conveyor engaging the forward end

of the fed partition and preventing further motion of the partition whereby the feeding action of the conveyor in connection with the stop collapses the partition, and a roller mounted above said conveyor serving as an auxiliary feeder to serve to force said partitions against said stop, said roller being mounted on an adjustable arm and a deflector positioned before said roller; said deflector engaging a corner of each of said partitions and causing them to rotate to a position where a diagonal of the partition extends parallel to the path of travel thereof; said deflector comprising a guide disposed in the path of travel of said partitions and at an angle thereto.

2. Apparatus for collapsing partitions comprising an endless belt conveyor for feeding said partitions, a stop at the end of said conveyor engaging the forward end of the fed partition and preventing further motion of the partition whereby the feeding action of the conveyor in connection with the stop collapses the partition, and a roller mounted above said conveyor serving as an auxiliary feeder to serve to force said partitions against said stop, said roller being mounted on an adjustable arm and a deflector positioned before said roller; said deflector engaging a corner of each of said partitions and causing them to rotate to a position where a diagonal of the partition extends parallel to the path of travel thereof; said deflector comprising a guide disposed in the path of travel of said partitions and at an angle thereto and a projection from said guide engaging said corner of each partition.

3. Apparatus for collapsing partitions comprising an endless belt conveyor for feeding said partitions, a stop at the end of said conveyor engaging the forward end of the fed partition and preventing further motion of the partition whereby the feeding action of the conveyor in connection with the stop collapses the partition, auxiliary feed means mounted above said conveyor to force said partitions against said stop, said auxiliary feed means being adjustable toward and away from said conveyor; and a deflector positioned before said roller; said deflector engaging a corner of each of said partitions and causing them to rotate to a position where a diagonal of the partition extends parallel to the path of travel thereof;

4. said deflector comprising a guide disposed in the path of travel of said partitions and at an angle thereto.

5. Apparatus for collapsing partitions comprising an endless belt conveyor for feeding said partitions, a stop at the end of said conveyor engaging the forward end of the fed partition and preventing further motion of the partition whereby the feeding action of the conveyor in connection with the stop collapses the partition, auxiliary feed means mounted above said conveyor to force said partitions against said stop, said auxiliary feed means being adjustable toward and away from said conveyor; and a deflector positioned before said roller; said deflector engaging a corner of each of said partitions and causing them to rotate to a position where a diagonal of the partition extends parallel to the path of travel thereof; said deflector comprising a guide disposed in the path of travel of said partitions and at an angle thereto; said stop being mounted on a movable carriage, said carriage moving away from the conveyor as the pile builds up.

20. 6. Apparatus for collapsing partitions comprising an endless belt conveyor for feeding said partitions, a stop at the end of said conveyor engaging the forward end of the fed partition and preventing further motion of the partition whereby the feeding action of the conveyor in connection with the stop collapses the partition, auxiliary feed means mounted above said conveyor to force said partitions against said stop, said auxiliary feed means being adjustable toward and away from said conveyor, and means located before said roller for rotating each of said partitions to a position where a diagonal of the partition extends parallel to the path of travel thereof.
